(57) **CLAIM**

I claim the ornamental design for a hand controller, as shown and described.

DESCRIPTION

FIG. 1 is a top view showing the new design.

FIG. 2 is a right side view showing the new design.

FIG. 3 is a left side view showing the new design.

FIG. 4 is a rear view showing the new design.

FIG. 5 is a third perspective view showing the new design.

FIG. 6 is a first perspective view showing the new design.

FIG. 7 is a second perspective view showing the new design.

FIG. 8 is a bottom view showing the new design; and,

FIG. 9 is a front view showing the new design.

1 Claim, 8 Drawing Sheets
